UNITED STATES PATENT OFFICE

FRANK M. ZIMMERMAN, OF AURORA, ILLINOIS.

ANCHOR FOR GUYS.

No. 876,127.

Specification of Letters Patent.

Patented Jan. 7, 1908.

Application filed June 6, 1907. Serial No. 377,520.

To all whom it may concern:

Be it known that I, FRANK M. ZIMMERMAN, a citizen of the United States, residing in Aurora, Kane county, Illinois, have invented certain new and useful Improvements in the Construction of Anchors for Guys to Trolley and Telegraph Poles and Like Uses, of which the following is a full and correct description of the same, reference being had to the hereto accompanying drawing, forming a part hereof, and in which—

Figure 1 shows my said new anchor in side elevation, in closed condition ready to drive into the earth; Fig. 2 shows a side elevation of the same, partly in section, and having the top part removed, the same being in open position; and Fig. 3 also shows the same in open position in top plan view.

Like reference letters denote like parts in all figures.

The object of my invention is to construct a ground anchor for guys to trolley, telephone and telegraph poles, and like devices, which shall be economical in construction and of easy entrance into the ground and therein have great resisting capacity after it has once settled to its place. To attain said desirable ends I construct my said new anchor in substantially the following manner, namely; I cast a long anchor-body *a* which is substantially square in cross section, and provided with rounded corners and with a point *a'* and above said point the body has superimposed transverse slots *b* and *b'* which receive the broad ends *d'* of the anchor-blades *d*. The planes of said parts are at right angles to each other, and, at their slot-ends, turn on pivots *e* and *e'* passed through the body *a*. Said broad and pivoted parts *d'* are so shaped at their edges as to meet the stops *f* and *f'* at the bottom and top of said slots *b* and *b'* when the blades *d* are extended or spread out to their anchoring position, which is the position indicated in Figs. 2 and 3. A shoulder *a''* at the upper end of the

body *a* receives the end of a strong tubular driver, on the other end of which falls driving mechanism for driving the anchor into the ground. A rod *c* is screwed axially into the upper end of the body *a* and its upper end is provided with an eye or ring *c'* screwed onto the end of said rod.

The device is driven into the ground in the closed condition, shown in Fig. 1. A reverse or withdrawing motion causes the outwardly curved ends *g* of the blades *d* to catch in the earth and thereby causes the said blades to turn on their pivots *e* and *e'* until the edges of the slot-ends of said blades *d'* rest on the slot-ends, or stops *f* and *f'* as shown in Fig. 2, when the motion of the blades *d* ceases and no farther withdrawal of the anchor will be possible without breaking away all the earth it can hold.

What I claim is:

65

1. The combination with an anchor-body provided with a point at one end and superimposed transverse slots above said point, of pivoted anchor-blades with ground catching outer ends, and stops at diagonally opposite slot-ends for the pivot-ends of said blades.

70

2. The combination with a pointed anchor-body provided with a transverse slot, a shoulder and an axial rod, threaded at each end, and an eye on said rod, of pivoted blades in said slot and diagonally opposite stops in said slot.

75

3. The combination with a pointed anchor-body, shouldered at its upper end and provided with an axial rod an eye therefor and superimposed transverse slots above said point, of pivoted anchor-blades in said slots and diagonally opposite stops therefor at each slot-end and outwardly bent ground-catching outer ends for each blade.

80

FRANK M. ZIMMERMAN.
